UNITED STATES PATENT OFFICE.

GEORGE HOWARD LYLE, OF BEN AVON, PENNSYLVANIA.

METALLIC TIE FOR RAILROADS.

SPECIFICATION forming part of Letters Patent No. 722,373, dated March 10, 1903.

Application filed September 22, 1902. Serial No. 124,301. (No model.)

To all whom it may concern:

Be it known that I, GEORGE HOWARD LYLE, a citizen of the United States, residing at Ben Avon, in the county of Allegheny and State of Pennsylvania, have invented or discovered new and useful Improvements in Metallic Ties for Railroads, of which the following is a specification.

In the accompanying drawings, which make part of this specification, Figure I is a perspective of a tie and rail fastening involving my invention; Fig. II, a side elevation thereof, showing the road-bed in section along the center line of the tie, the ballast at one end being omitted; and Fig. III, a perspective of a rail-holding clip of a form slightly different from that shown in the preceding views.

My invention relates to metallic ties for railroads; and its object is to provide a tie made of pressed steel or wrought-iron which will be comparatively light, exceedingly strong, and simple in its manufacture and application.

In the drawings, 1 is the tie proper, which consists of a strip of steel plate about six inches wide bent at each end as follows: The outer three inches is bent up vertically to form the flange 2. About six inches from the flange 2 the plate has the vertical limb or upstanding portion 3, which is about five inches high. The top of the limb 3 is joined by the inwardly-extending top 4, which is about five inches long, or the width of the flange of the rail 5 seated thereon. The inner end of the top 4 is joined by a vertical limb or upstanding portion 6, parallel to the limb 3 and having the same height. The limbs 3 and 6 and the tops 4 form benches or bases, which are connected together by the horizontal tie or connecting portion 7, connecting the bottoms of the limbs 3 and 6.

On Fig. II, I have shown a block 10, of cement or the like, which fills the space 9 and has horizontal shoulders 11 supporting the end portion 8 and that part of the portions 7 nearest the bench. This block 10 has a slot or hole 12 to receive the bolt 13, hereinafter referred to. The purpose of this block is not only to support the weight on the tie, but also to prevent lateral movement of the bench and to prevent any liability of the material in the space 9 flowing down unevenly under the por-

tions 7 and 8 of the ties, as it might do under the vibration due to the passing of a large number of cars.

Any suitable filling material, as ordinary ballast 19, lies under the tie between the blocks 10 and covers the tie between the rails and the ends thereof beyond the rails. The ballast on the outer sides of the rails by engagement with the flanges 2 and the benches resist the lateral thrust or the bending of the ties. Under same conditions the spaces occupied by the blocks 10 could be filled with ballast.

I may strengthen the meeting angles of the portion 8 and the limb 3 of the tie by means of the rib 14, pressed out to form a brace, as shown. This rib may be used with or without the block 10 or the ballast in the space 9. It will probably be needed, if at all, only at the outer sides of the benches, as shown on Fig. I, but may be used at the inner sides thereof when necessary. Whether the ballast, the cement, or the rib will be used alone or the latter will be used with the ballast or cement will depend upon the strains the tie will be subject to.

The rails are laid on the benches transversely of the ties, as shown in Figs. I and II. To hold the rails on the benches, I provide for each bench two clips, each having a vertical body portion 15, two vertical end flanges 16, and an inclined top flange 17. The top flange 17 of the clip is bent so as to fit the outer top portion of the flange of the rail when the body portion 15 fits closely against the outer sides of the top portion of the limb 3 or 6. The body portions 15 of the clips are as wide as the tie, and the end flanges are bent closely against the edges of the limbs 3 and 6 of the benches, the flanges preferably terminating flush with the inner surface of the said limbs. A clip is placed on each side of each bench, as shown in Figs. I and II, and the headed bolt 13, having a nut 18, is passed through alined holes in the bench and the clips and secures the rail rigidly in its place on the bench. The clips may have the top flanges as wide as the tie, as shown in Fig. I, or as wide as the combined width of the body portion 10 and the end flanges 11, as shown in Fig. III.

I do not limit myself to the precise dimen-

sions, material, or construction above described, as many modifications thereof may be made which come within the scope of my invention.

5 Having described my invention, I claim—

1. A metal tie made of a plate bent near the ends into upstanding benches, each bend being continuous across the whole width of the tie, in combination with means for holding the rails firmly on the benches.

15 2. A metal tie made of a plate bent at its ends into flanges and near the ends into upstanding benches, each bend being continuous across the whole width of the tie, in combination with means for holding the rails firmly on the benches.

15 3. A metal tie made of a plate bent near the ends into upstanding benches, and strengthening-ribs at the angles of the benches, in com-

bination with means for holding the rails 20 firmly on the benches.

4. A metal tie bent at opposite ends to form upstanding rail-supporting benches, clips on the benches constructed to overlie the flanges of the rails, and means for holding the benches 25 and the clips assembled.

5. A rail-supporting base, and a clip secured to the side of the base and having a flange lying on the rail-flange to hold the rail on the base and end flanges lying against the 30 ends of the base to prevent movement of the clip.

Signed at Pittsburg this 19th day of September, 1902.

GEORGE HOWARD LYLE.
